UNITED STATES PATENT OFFICE.

FRANK L. LINDEN, OF CHICAGO, ILLINOIS.

DESIGN FOR A BRACKET PLATE FOR LIGHTING FIXTURES.

Application filed December 21, 1925. Serial No. 15,805. Term of patent 3½ years.

To all whom it may concern:

Be it known that I, FRANK L. LINDEN, a citizen of the United States, residing at Chicago, in the county of Cook and State of Illinois, have invented a new, original, and ornamental Design for Bracket Plates for Lighting Fixtures, of which the following is a specification, reference being had to the accompanying drawing, forming a part thereof.

On the drawing:

Figure 1 is a front elevational view, and Figure 2 is a side elevational view, showing my new design.

I claim:

The ornamental design for a bracket plate for lighting fixtures, as shown.

In witness whereof, I hereunto sign my name this 15th day of December, 1925.

FRANK L. LINDEN.
